STAPLE SUPPORTER FOR STAPLING MACHINES

Filed Sept. 22, 1945

UNITED STATES PATENT OFFICE

2,431,548

STAPLE SUPPORTER FOR STAPLING MACHINES

Arvid I. Ericsson, Chicago, Ill., assignor to Signode Steel Strapping Company, Chicago, Ill., a corporation of Delaware

Application September 22, 1945, Serial No. 618,048

3 Claims. (Cl. 1—49)

1

This invention relates to staplers, and more particularly to a staple hammer which provides support for the staples against collapse, crumpling, or mutilation as they are driven into the work.

In the use of staplers, and particularly staple hammers, staples often collapse and become crumpled while being driven into the work, so that they are ineffective and unsightly and must be replaced. This causes inconvenience, loss of time, and in some cases waste of material being stapled or, if the staples are not replaced, the appearance is poor. The present invention provides means in the stapler which supports the staple against collapse as it is being driven into the work.

It is an object of this invention to provide a stapler having means to prevent collapsing of a staple being driven into an object.

It is another object to provide a stapler which will drive a staple securely into the work even though the staple does not enter the work squarely.

Other objects will appear from the following description, reference being had to the accompanying drawings, in which:

Fig. 1 is a side elevational view of a staple hammer incorporating my invention;

Fig. 2 is an enlarged fragmentary sectional view of the head portion of the stapler illustrated in Fig. 1, showing the parts in one position;

Fig. 3 is a view similar to Fig. 2, but showing the parts in a second position;

Fig. 4 is a view similar to Figs. 2 and 3, but showing the parts in a third position;

Fig. 5 is a vertical sectional view taken along the line 5—5 of Fig. 3; and

Fig. 6 is an enlarged fragmentary view taken along the line 6—6 of Fig. 1.

This invention as illustrated is applied to a staple hammer of the general type disclosed in Henry Keil Patent No. 2,345,267, issued March 28, 1944, although it will be understood that the invention may be applied to staplers of other types.

For the sake of brevity and clearness, the structure and operation of the invention are described below as though the stapler were always in substantially the position illustrated in the drawings, with the staple driving head portion thereof substantially vertical for driving a staple downwardly, although actually the stapler may be employed in any position.

The staple hammer comprises a head portion 10 and a hollow handle portion 12 which serves as a staple magazine. Staples 14, which may be

2

detachably secured together in a stick as common in the art are urged toward the forward end of the handle portion 12 by a spring disposed in a spring housing 16 carried by the handle portion. At the forward end of the handle portion 12, the staples pass over a staple guide 18 defining with the handle a gateway 19 corresponding to the shape of the staples and opening into a guideway 20 disposed at right angles to and extending upwardly from the handle portion 12. The guideway 20 has a width only sufficiently larger than the width of the staple to enable the staple freely to slide therein and a depth sufficient to receive only a single staple. The guideway 20 is formed in the striking member 26 which is slidably engaged on the guide 24 (formed on the head of the stapler) by means of rearwardly extending side flanges 28 and inwardly extending rear flanges 30 at the rear ends of the flanges 28 embracing the guide 24. The forward face of the staple guide 18 lies in the plane of the bottom of the guideway 20. The striking member 26 normally projects below the handle portion 12, so that the guideway 20 therein normally extends below the lower end of the staple guide 18. Thus the guideway 20 is progressively moved downwardly upon downward movement of the handle portion 12. A staple driving member 32 is disposed in the guideway 20 with its lower end normally disposed above the staple gateway 19.

The driving member 32 has a sliding fit in the guideway, and its bottom edge is adapted to engage the head of a staple 14 in the guideway to drive the staple downwardly into the work. An inertia member 34 may be connected to the driving member 32, and suitable mechanism may be associated therewith to increase the driving force of the member 32, particularly at the end of its stroke. Arms 36 secured to the handle portion 12 at each side thereof serve as stop means to limit relative movement between the striking member 26 and the driving member 32 and inertia member 34. Lugs 38 are provided on the striking member 26 which are engageable with the arms 36 to limit relative upward movement of the striking member. A rack 40 at one side of the striking member which forms part of the mechanism of the inertia member 34 is engageable with one of the arms 36 to limit relative downward movement of the striking member. The bottom of the inertia member 34 is engageable with the arms 36 to limit relative downward movement of the driving member 32 and inertia member 34, and a spring 42 is provided to return

the members 26, 32, and 34 to their normal positions.

When a staple is to be driven, as into the work 44, the stapler is swung so that the bottom of the striking member 26 is brought forcefully against the work, and thus is moved upwardly relative to the handle portion 12 and driving member 32. The handle portion and driving member move downward relative to the striking member, and the driving member 32 also moves downwardly relative to the handle portion 12, engaging the staple 14 in the guideway 20 and driving it into the work 44. The driving member 32 moves downwardly faster than the handle portion 12 and guide 24, but the relative speeds are such that the forward end of the handle portion contacts the work before the driving member. The staple 14 thus moves downwardly relative to the guide 24, but a portion thereof remains engaged in the guideway 20 until the staple is fully driven into the work. When the staple has been driven, the striking member 26 is removed from contact with the work and the parts are returned to their original or normal positions by the spring 42. As the driving member 32 moves upwardly beyond the staple gateway 19, another staple 14 is urged into the guideway 20. This staple may then be driven in the manner already described. Structural and operational details of the stapler as so far described are disclosed in the aforesaid patent, and reference may be had thereto for a full explanation.

The width of the guideway 20 is such that the outer surfaces of the legs of a staple 14 are substantially in contact with the side walls thereof, and the width of the driving member 32 of course corresponds to the width of the guideway. The legs of the staple 14 thus are supported against moving or collapsing outwardly as the staple is driven downwardly in the guideway 20 and into the work 44.

To prevent the legs of the staple from moving or collapsing inwardly as it is driven into the work, a movable support member 50 is provided at the lower end of the striking member 26. The forward wall of the striking member 26 adjacent the bottom thereof is formed to provide a recess forwardly of and opening into the guideway 20. The width of the recess 46 corresponds to the distance between the inside of the legs of a staple 14, so that a portion 20a of the bottom wall of guideway 20 extends along each side of the recess 46 to support a staple as the guideway 20 passes the recess 46. The width of each portion 20a thus corresponds to the thickness of a leg of the staple. A pin 48 extends through the recess 46 with its ends secured in the side walls thereof. The movable support member 50 is pivoted on the pin 48. The member 50 is bifurcated to provide spaced stop portions 52 at the upper end thereof, and a toe portion 54 is formed at the lower end thereof. A spring 56 on the pin 48 between the stop portions 52 has one end bearing on the forward or end wall of the recess 46 and the other end engaging the toe portion 54. The spring normally holds the support member 50 with the toe portion extending through the guideway 20 and the stop portions 52 engaging the end wall of the recess. The stop portions 52 thus limit pivotal movement of the support member under the influence of the spring 56, and therefore the position of the toe portion 54 in the guideway 20. The toe portion extends the width of the recess, having a length substantially equal to the distance between the staple legs and fit-

ting snugly between the legs. The end surfaces of the toe portion 54 thus support the staple legs against moving or bending inwardly when the staple straddles the toe portion.

5 The lower surface 58 of the toe portion 54 is rounded or otherwise shaped so as to clear the work 44 as the support member 50 pivots on the pin 48.

10 The upper surface of the toe portion 54 is formed to provide a cam, illustrated as comprising an upper cam surface 60 extending at an angle downwardly into the guideway 20 when the support member is in its normal position, and a lower cam surface 62 extending at such an angle to the cam surface 60 as to be more or less horizontal in normal position. As will be clear from Figs. 2 to 5, when the staple 14 is driven downwardly by the driving member 32, the legs of the staple are engaged between the end surfaces of the toe portion 54 and the side walls of the guideway 20 in the striking member 26. The legs of the staple are thus supported against bending or buckling either inwardly or outwardly, and the engagement of at least a portion of the staple in the guideway 20 prevents movement thereof forwardly or rearwardly. The staple legs are most likely to buckle or bend when they first come into contact with the work 44, particularly if a relatively hard material is encountered. The disposition of the support member 50 at the bottom of the striking member, closely adjacent the work, provides support against buckling of the staple at the point where it is most necessary.

20 As the staple moves into the work, the head 35 of the staple contacts the support member 50, first engaging the upper cam surface 60 on the toe portion 54, and the downward movement causing the support member 50 to pivot against the force of the spring 56 so as to swing the toe portion 54 partially out of the guideway 20. This movement brings the upper cam surface 62 into a downwardly and rearwardly angled position, and continued downward movement of the head of the staple further pivots the support member 40 to move the toe portion 54 entirely out of the guideway 20 and out of the path of the head or cross-bar of the staple, which can then move downwardly so that the staple may be fully driven into the work 44. It will be clear that until the 45 head of the staple cams the toe portion 54 entirely out of the guideway 20, the toe portion supports the legs of the staple closely adjacent to the work 44 against inward collapse.

50 With the construction described, the staple 55 14 is prevented from buckling and becoming crumpled or mutilated so that it cannot perform its intended securing function. Such collapse of the staple might result from a blow of the stapler in which one side of the striking member contacts the work before the other; so that the staple enters the work at an angle, from inclusion in the work 44 of a relatively hard material resisting penetration by the staple, or other causes. Since the construction described prevents collapsing of the staple legs, and since the driving member 32 has full engagement with the upper surface of the head of the staple to provide substantially equal distribution of the driving force, the staple legs must enter the work in substantially straight condition, and the staple is driven smoothly into securing position.

55 Having thus described my invention, what I claim as new and desire to secure by Letters Patent is:

70 1. A hammer type stapler comprising a staple

magazine, a head secured to the forward end of the magazine, a striking member movable vertically across the front face of the head, a staple guideway formed in the striking member into which staples are fed from the magazine, a staple driver carried by the head and movable relative to the striking member through the staple guideway, and means for feeding staples one at a time from the magazine into the guideway below the driver, characterized by a recess formed in the lower end of the striking member and open to the staple guideway, a staple supporter pivotally mounted within said recess, said supporter comprising a member having a rear face formed of a pair of adjacent cam surfaces disposed at an angle relative to each other, said member having a pair of opposed side surfaces engageable by the legs of a staple in the staple guideway, said side surfaces and the walls of the staple guideway serving to prevent collapse of the legs of the staple as it is driven into the work, and means biasing said member so that it normally projects across the guideway with the uppermost of the cam surfaces positioned in the path of a staple, whereby during the operation of the stapler the head of a downwardly moving staple first engages the upper cam surface to swing said member downwardly about its pivotal mounting so as to bring the second of said cam surfaces across the staple guideway for further pivotal movement of said member by the moving staple.

2. A hammer type stapler comprising a staple magazine, a head secured to the forward end of the magazine, a striking member movable vertically across the front face of the head, a staple guideway formed in the striking member into which staples are fed from the magazine, a staple driver carried by the head and movable relative to the striking member through the staple guideway, and means for feeding staples one at a time from the magazine into the guideway below the driver, characterized by a recess formed in the lower end of the striking member and open to the staple guideway at its discharge end, a staple supporter pivotally mounted within said recess, said supporter comprising a member having a rear face formed of a pair of adjacent cam surfaces disposed at an angle relative to each other, said member having a pair of opposed side surfaces engageable by the legs of a staple in the staple guideway, said side surfaces extending upwardly from the discharge end of the guideway to co-act with the walls thereof to prevent collapse of the legs of the staple as it is driven into the work, and means biasing said member so that it normally projects across the guideway with the uppermost of the cam surfaces positioned in the path of a staple, whereby during the operation of the stapler the head of a down-

wardly moving staple first engages the upper cam surface to swing said member downwardly about its pivotal mounting so as to bring the second of said cam surfaces across the staple guideway for further pivotal movement of said member by the moving staple.

3. A hammer type stapler comprising a staple magazine, a head secured to the forward end of the magazine, a striking member movable vertically across the front face of the head, a staple guideway formed in the striking member into which staples are fed from the magazine, a staple driver carried by the head and movable relative to the striking member through the staple guideway, and means for feeding staples one at a time from the magazine into the guideway below the driver, characterized by a recess formed in the lower end of the striking member and open to the staple guideway at its discharge end, a staple supporter pivotally mounted within said recess, said supporter comprising a member having a rear face formed of a pair of adjacent cam surfaces disposed at an angle relative to each other, said member having a pair of opposed side surfaces engageable by the legs of a staple in the staple guideway, said side surfaces extending upwardly from the discharge end of the guideway a distance less than the length of a staple leg to co-act with the walls of the staple guideway to prevent collapse of the legs of the staple as it is driven into the work, a stop formed on said member and adapted to abut against the wall of the recess opposite its opening to the guideway, and spring means biasing said stop against the wall so that said cam surfaces normally project across the guideway with the uppermost cam surface positioned in the path of a staple, whereby during the operation of the stapler the head of a downwardly moving staple first engages the upper cam surface to swing said member about its pivotal mounting so as to bring the second of said cam surfaces across the staple guideway for further pivotal movement of said member by the moving staple.
